(57) **CLAIM**

The ornamental design for an audio player, as shown and described.

DESCRIPTION

FIG. 1 is a front, right side, perspective view of an audio player showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front, right side, perspective view of the audio player shown in an environment of use, mounted on a stand; FIG. 9 is a front, right side, perspective view of the audio player shown in another environment of use, mounted on a stand; and,

FIG. 10 is a front, top, perspective view of the audio player shown in another environment of use, mounted on a stand. The broken line showing of the stand in FIGS. 8, 9 and 10 is provided for the purpose of illustrating environmental structure that forms no part of the claimed design.
